UNITED STATES PATENT OFFICE.

WEBSTER E. B. BAKER, OF YORK, PENNSYLVANIA.

RIBBON FOR TYPEWRITING AND SIMILAR MACHINES.

Application filed March 11, 1919. Serial No. 282,016.

To all whom it may concern:

Be it known that I, WEBSTER E. B. BAKER, a citizen of the United States, and residing at York, county of York, State of Pennsylvania, have invented certain new and useful Improvements in Ribbons for Typewriting and Similar Machines, of which the following is a specification.

The present invention relates to inking 10 ribbons or sheets such as are employed in printing mechanisms in which the ink is not applied directly to the impression means, for example, typewriting, multigraphing, and adding machines, and time and dating 15 stamps. Type operating with prior ribbons do not produce clear, solid-line impressions, such as are obtained by the type acting directly on the printing surface, for the reason that the surface of prior ribbons have 20 not been smooth. Thus the threads of fabric ribbons and the surface roughness of paper ribbons interrupt the continuity and evenness of the impressions. The unevenness and blurring obtained with prior ribbons are particularly noticeable when compared with the printing or engraving of 25 letterheads, or other printed matter appearing on the same sheet.

The principal object of the present invention is to eliminate the defects of prior inking ribbons and provide a ribbon which will produce clean cut solid-line printing in harmony with printing, engraving or embossing which may appear on the same sheet.

To these ends an inking ribbon or sheet 35 constructed in accordance with this invention comprises a base which is treated so as to present a smooth, hard surface thus eliminating the inequalities in the impressions 40 due to the structure of the material forming the base. Preferably this is accomplished by applying to the base a suitable material to fill up the interstices in the base and provide a smooth, uninterrupted hard surface 45 on at least one side of the base. Preferably a base is employed comprising a fabric such as cotton or silk as thin as possible consistent with the required strength and durability, although the invention is applicable 50 to other materials, such as paper. To this base is applied as by impregnating or coating a substance which will adhere securely to the same, fill up the interstices and form a sheet which presents a hard, smooth surface and yet is flexible. For this purpose, I 55 have found any of the substances of the cel-

lulose-ester group to be satisfactory, and also starch-esters. As examples of these substances viscose and starch acetate may be employed, but I prefer viscose. A base 60 coated or impregnated with such a substance presents a hard, smooth surface and the substance will hold and to some extent absorb ink. Furthermore, because of the smooth, uninterrupted hard surface thus formed the 65 impressions obtained are even, sharp, and clear, like printing obtained from inked type. Other objects and features of the invention will be apparent from the description taken in connection with the drawings in 70 which:

Figure 1 is an enlarged sectional view of an inking ribbon or sheet constructed in accordance with the present invention; and Figure 2 is a similar view of another form 75 of the invention.

Referring to Figure 1, the reference letter *a* indicates the base of a ribbon which is of any suitable material, preferably silk or cotton. To this base is applied a substance 80 which will produce a tough, smooth-surfaced, flexible sheet. A substance such as previously mentioned is preferably employed and may be applied under pressure as a coating *b*. The pressure will force the substance 85 into the interstices of the base so that at least one surface of the sheet is smooth and uninterrupted. To this smooth surface a suitable ink *c* is applied, and to some extent this coating of ink will be absorbed by the substance of the coating *b*.

In Figure 2 another form of the invention is illustrated. The inking sheet of this form is like that described above, but a coating *d* is applied on the surface of the base opposite 95 the coating *b*. The coating *d* consists of the same material as the coating *b* and the material with which the base is impregnated. The impressions obtained when using a ribbon as illustrated in Figures 1 and 2 will be 100 even, unblurred and solid-lined, for the reason that the effect of the threads, fiber, grain or roughness of the base has been eliminated by the viscose or other material with which the base is impregnated. Furthermore, as 105 the viscose or similar material possesses considerable strength, and absorbs the blows of the type striking on the ribbon, the base itself may be made thinner than heretofore. In fact the entire thickness of a ribbon constructed in accordance with this invention is 110 less than the usual prior ribbons, and con-

sequently a greater length of ribbon may be stored in a given space.

The feature that the present ribbon is thinner than prior ribbons contributes to obtaining the clear cut solid-line printing previously mentioned, as obviously the thinner the ribbon, the clearer the impression. It is well known that substances of the cellulose-ester group such as viscose are stronger when moist than when dry. In the present instance the ink maintains the coating more or less moist, whereby the maximum strength of the coating is obtained. This feature in turn permits the use of a coating of the minimum thickness.

An inking sheet, according to this invention does not act to fill up the type with ink and fiber from the fabric of the ribbon, for the reason that in the form of Figure 2 the coating *d* prevents this and in the form of Figure 1, the base is dry on the side struck by the type.

Although specific embodiments of the invention have been described, it is to be un-

derstood that the invention is not thus limited but includes modifications and changes which come within the scope of the appended claims.

Having thus described the invention what is claimed as new and desired to be secured by Letters Patent is:

1. A sheet of the character described, comprising a base coated on both faces with a tough, smooth, flexible material, and a suitable ink applied to one of the surfaces of the coated sheet.

2. A sheet of the character described, comprising a base coated on both faces with a tough, smooth, flexible substance of the cellulose-ester group, and a suitable ink applied to one of the surfaces of the coated sheet.

3. A sheet of the character described, comprising a base coated on both faces with viscose, and a suitable ink applied to one of the surfaces of the coated sheet.

In testimony whereof I affix my signature.

WEBSTER E. B. BAKER.
